UNITED STATES PATENT OFFICE.

BURTON W. SWEET, OF CLEVELAND, OHIO, ASSIGNOR TO HARRY Z. SANDS, OF CLEVELAND, OHIO.

DETACHABLE TELEPHONE-SUPPORT.

1,002,783.

Specification of Letters Patent. Patented Sept. 5, 1911.

Application filed March 23, 1907. Serial No. 364,134.

To all whom it may concern:

Be it known that I, BURTON W. SWEET, a citizen of the United States of America, and a resident of Cleveland, in the county 5 of Cuyahoga and State of Ohio, have invented certain new and useful Improvements in Detachable Telephone-Supports, of which the following is a specification.

My invention relates to improvements in 10 separable supporting members specially designed for removably mounting a telephone instrument in convenient position for use, as at the end of an extensible pivoted arm.

The object of my invention has been the 15 production of a device of this character, which shall be simple, light and cheap, and to this end it preferably is formed of sheet metal. In my application, Serial No. 362,874, I have described a sheet metal extensible arm, with which I have chosen to 20 show my present improvement directly associated in the accompanying drawings. My said improvement is equally adapted for use in removably supporting one or more telephones 25 instruments in any position required, and I may briefly refer to the features thereof in a preliminary way, by stating that one member of said separable support, comprises an arm-section preferably flanged 30 to strengthen the same, and formed from an integral sheet metal blank. In a socket, provided in said member, the second member readily fits; the same comprising a cylindrical portion seated in said socket, and a 35 laterally extending wing or wings with which the telephone instrument is permanently connected. Thus said instrument will be securely held by the socketed member, but may be instantly taken in the hand 40 for use, and returned to the socket-member when out of use.

Further details of construction will be more readily gathered by making reference to the accompanying sheet of drawings, 45 forming a part of this specification, wherein:

Figure I is a view in side elevation partially broken away, showing the sheet metal supporting arm and the telephone support 50 of my invention. Fig. II is an enlarged detail, showing the removable member in side elevation and partially broken away. Fig. III is a top view thereof. Fig. IV is a perspective view of the socketed arm-section or support. Fig. V is a cross-sectional view

thereof; and Fig. VI is a plan view illustrating the employment of a plurality of said arm-sections for the support of a corresponding number of telephone instruments.

60

Throughout each of the several figures of the drawings, I have employed the same character of reference to indicate similar parts.

Referring first to Fig. IV, it is seen that 65 a socketed bracket, or arm-section *a*, is formed from an integral sheet metal blank of suitable shape, and affording rearwardly extending ears *a'* and reinforcing top and bottom flanges *a*². These latter stiffen or 70 strengthen the walls of a substantially cylindrical sockets *a*³ open at the front, and permit of relatively light construction, without impairing the strength of the bracket. The co-acting separable member 75 *b* is formed of an integral blank of sheet metal, affording a cylindrical portion *b'*, web *b*², and two laterally extending wings *b*³, through which screws *c*' extend to secure the telephone instrument or standard *c* 80 rigidly thereto. Preferably a pin bolt *b*^{3x} with a rounded or tapered terminal is enclosed within the cylindrical portion *b'* of the separable member, although this is not essential, if the metal be stiff enough to 85 avoid collapse or deformation. One or more of the flanges *a*² may also be dispensed with under like conditions, but preferably these features are employed as herein shown and described.

90

The ears *a'* are rearwardly connected by a pivotal bolt *d*, with the adjacent arm-section *e* of the pivoted extension-arm, or if no pivotal motion of the outer arm-section is desired, this joint may be made rigid 95 simply by tightening said bolt.

Where a plurality of telephone instruments are to be accommodated upon a single arm, as indicated in Fig. IV, one of said arm-sections may be made longer than the 100 other, as *a*⁴, in order to avoid interference, while the several arm-sections preferably are pivoted so that any one of the telephones may instantly be turned into position for use. In the extension-arm, shown in Fig. I, 105 which equally with other suitable means, may be employed to carry my improved separable supporting appliance, the arm-section *e* is united by a pivotal joint *f* with the inner arm-section *g*, which in turn is 110

carried upon a pivotal joint *h* by means of a stationary sheet metal bracket *j*. Each of these arm-sections *e* and *g* is formed of a single strap of sheet metal, preferably key stock, bent to afford integral sockets at either end, with a rigid intermediate body portion, thereby affording a strong and servicable extensible arm.

From the foregoing, it will be seen that 10 the telephone instrument, when mounted for support upon my separable sheet metal bracket members, is readily turned upon its pivotal mountings into any desired position for use, while held securely in place, or on 15 the other hand if the telephone user wishes to take the instrument in his hands for greater convenience, the separable members admit of instant detachment for this purpose, since one member fits loosely within 20 the socket of the other. Where a plurality of such instruments are employed, as where local or intercommunicating instruments are required, as well as a long distance telephone, for example, each of these instruments 25 is instantly available, and having its own receptacle, the connecting cords thereof are not liable to become tangled, twisted or broken. As before, the pivoted arm-sections permit the telephones to be turned individually into the most convenient position for 30 use.

The separable bracket members, constructed principally from stampings as they are, combine the qualities of extreme cheapness with maximum strength and durability, and the device commends itself by meeting 35 the requirements of ordinary service.

Having now described the preferred embodiment of my invention, I claim and desire to secure by Letters Patent, the following:—

1. In a device of the class described, the combination with a socket member formed of an integral sheet metal blank affording a substantially cylindrical socket or recess 45 cut by a lateral opening or slot, and overturned flanges adjacent to the top and bottom thereof, of a separable coacting supporting member shaped from sheet metal to afford a cylindrical engaging part presented to the socket member, and an integral attaching part or lug for the supported instrument, substantially as set forth. 50

2. In a device of the class described, the combination with a socket member formed of an integral sheet metal blank, comprising a substantially cylindrical socket portion having a vertical opening and an attaching part therefor, of a separable co-acting supporting member formed of an integral sheet 55 metal blank, comprising a substantially cylindrical engaging part adapted to enter said socket-portion; the same having a vertical web and an attaching lug adapted to be secured to the telephone instrument, substantially as set forth. 60

3. In a detachable telephone support, the combination with a pivotal arm-section, comprising integral ears, a cylindrical socket forwardly open, and an encircling 70 flange, of a separable member comprising a cylindrical body portion, a web, and attaching lugs adapted to be secured to the telephone standard, substantially as set forth. 75

Signed at Cleveland, this 8th day of March, A. D. 1907, in the presence of two subscribing witnesses.

BURTON W. SWEET.
